RIBBON INKING DEVICE

Paul E. Vega, New York, N. Y., assignor to The Associated Press, New York, N. Y., a corporation of New York

Original application July 31, 1936, Serial No. 93,576. Divided and this application July 22, 1938, Serial No. 220,624

6 Claims. (Cl. 197—171)

This is a division of application Serial Number 93,576, filed July 31, 1936.

This invention relates to an inking device for typewriter ribbons.

Application Serial No. 93,576 referred to above discloses a Multiple copy system by which a number of copies may be made from a single typewriter ribbon guided between webs of paper arranged in a series of layers, thus dispensing with the use of carbon paper, and an object of the present invention is the provision of a mechanism for automatically inking ribbons adapted for use in connection with such multiple copy systems when applied to automatic telegraph printers.

A further object is the provision of an inexpensive mechanism which may be attached to present printers without the necessity of drilling, tapping, or in general, requiring any skilled mechanical labor on present printer structures.

Other objects will appear in the following description given with the aid of the accompanying drawings of which there are two sheets.

Referring to the drawings:

Figure 1 is a plan view of a printer top.

Figure 2 is a plan view of the left hand inking mechanism.

Figure 3 is a plan view of the right hand inking mechanism.

Figure 4 is a front elevation of the right hand inking mechanism partly in section, the section being taken through 4—4 of Figure 3.

Figure 5 is a front elevation of the right hand inking mechanism.

Figure 6 is a section taken through 6—6 of Figure 3.

Figure 7 is a section taken through 7—7 of Figure 6.

The particular modification of the present invention is designed for use in connection with a well-known Teletype page printer of which a great many are in use. This printer is described in detail in Patent No. 1,665,594 issued to H. L. Krum, April 10, 1928, and therefore only brief reference will be made to the printer mechanism per se.

The invention now about to be described may be attached to the Krum printer referred to above, by means of the two front cover screws.

The reference character 1 indicates a conventional printer top having ribbon spools 10 and 11.

An inking mechanism is provided for both spools, either or both of which may be tripped at any time, but which will not become effective until the ribbon starts to reverse, and which

after inking for a ribbon feeding cycle will automatically disengage itself. If an inking device were used which would be immediately effective when operated, in most cases the ribbon would be unevenly inked unless an attendant were on hand to cause the device to engage just as the ribbon reversed and to disengage it at the next reversal instant.

The inking mechanism is supported by a bar 40. Figure 1, secured to the top of casting 1 of the printer by means of screws 41 which also secure the front part of the top casting to the printer frame. Bar 40 is bent downward and thence outward on each side of the printer frame forming a short vertical section 42, and a short horizontal section 43.

In the following description it will be understood that the parts referred to are duplicated at opposite ends of the printer, and in some cases the parts are formed so as to bear a right hand or left hand relationship to each other.

Lever 44 is pivoted by screw 45 to 43 has an ink pot 46 rigidly secured thereto, the ink pot being provided with a cover 47 and a spout 48 which is cut away for a short distance from its end at 49 forming a support for wick 50 which may ride, when the device is engaged, on ribbon 12 on the ribbon spools, as shown in Figure 3.

Spring 51 tends to move lever 44 and ink pot toward the adjacent spool, but is normally restrained from doing so by latch 52, Figure 2, pivoted on screw 33 to vertical plate 53 secured by screws 54 to 43. The latch is notched or cut away so as to form an upright part 55 which is constantly urged against the underside of lever 44 by spring 56, so that when the lever is reset by means described below, the beveled face 55 of the latch locks lever 44 in its outermost position holding the ink wick away from the ribbon.

A second latch 57 cooperates with latch 52, the action of the two latches being in the nature of an escapement.

Latch 57, shaped like a bell crank, is pivoted by 58 to plate 53. Spring 59 tends to press the latch against the upper surface of lever 44. When the inking device is in its unoperated or reset position, lever 44 is held only by the face 55 of latch 52, the face 60 of latch 57 being in the path of lever 44 but spaced approximately $\frac{1}{64}$ of an inch away, as indicated in Figures 2, 3 and 4, so if manually operated latch 52 is disengaged, lever 44 moves a short distance until it stops against face 60 of latch 57 which renders latch 52 ineffective, and lever 44 is restrained in an ineffective intermediate position for the time.

A pawl 61 is pivoted by pivot 62 to the upwardly extending arm of latch 57. Spring 63 holds the slanting face of the pawl against stop 64 formed by a bent over part of the upright arm of latch 57.

5 Latch 57 is controlled by the printer ribbon feed mechanism through the agency of a sliding bar 65 extending clear across the top of the printer. The bar is guided and supported by a slot formed by plates 66 and 67 located at each end of the 10 printer and secured by screws 68 to the vertical part 42 of bar 43. Stop pins 680 are inserted in the bar to limit its movement. Both ends of bar 65 are bent downward and the inner surface of the depending parts are bevelled to form cam surfaces 69, each of which is adapted to engage the slanting face of the adjacent pawl 61, while the 15 respective noses 70 on the outer surface of the bar are adapted to engage the vertical part 71 of the adjacent pawl depending on the direction in which bar 65 is moved.

20 Bar 65 carries two bell crank shaped pawls, each having an outwardly extending arm with faces 72 and 73. The pawls are pivoted on screws 74 to bar 65. Springs 75 tend to hold arms 76 25 against stops 77 in bar 65.

25 Bar 65 may be moved in either direction, depending on which ribbon spool is winding up, by pins 78 which in the present embodiment project downward from the under side of the ribbon spool 30 and engage either of the pawls. Obviously a disc or bar, or other suitable arrangement could be attached to the ribbon spool spindles, or other convenient part of the winding mechanism to carry pins 78 or other suitable tripping means in 35 place of the arrangement shown in the present embodiment.

40 Referring to Figure 2 where the left hand ribbon spool is represented as turning counter-clockwise and unwinding the ribbon, pawl face 72 is shown in position to be engaged by pins 78. As the ribbon spool turns, repeated contacts of pins 78 with face 72 of the pawl merely rotate the latter on its pivot away from stop 77 to which it is immediately restored by spring 45 75. However, when the ribbon reverses, the ribbon spool will turn in a clockwise direction and now face 73 of the pawl will be engaged by a pin 78, and since the pawl is held against rotation in this case by its pivot 74 and stop 77, the continued 50 rotation of the spool will force bar 65 to the left of the position shown in Figure 2, tripping latch 57. The corresponding mechanism for the right hand side of the printer shown in Figure 3 now 55 has changed so that the pawl face 72 is in position to be engaged by pins 78 until the spool is unwound, and then when the right hand spool reverses and starts to rewind, pin 78 engages face 60 73 of the pawl, which cannot rotate on its pivot in this direction, and bar 65 is moved toward the right, tripping latch 57, and if latch 52 had been 65 previously operated, then the respective parts of the mechanism would occupy the position shown in Figures 3 and 4.

65 The inking mechanism is reset by toggle mechanism mounted on levers 44 which consists of a U-shaped lever 80 pivoted on stud 81 secured at the end of lever 44.

70 Spring 82 tends to hold 80 against eccentric stop screw 83 which may be adjusted according to the length of the ribbon on the spools. At the end of the upper arm of lever 80 is a bifurcated lever 85 having arms 86 and 87, the lever being supported by pivot screw 84. The opposite end 75 of the lever, adjacent to the pivot, is bent down-

ward forming a stop 88 which is held in engagement with the side of lever 80 by spring 89.

Operation

5 The device operates as follows: Assume that the printer is operating, and both inking devices are in their normal position out of contact with the ribbon on the respective ribbon spools: If it be desired to put both inking devices into operation, the ends of both latches 52 are manually lifted releasing lever 44 which, however, move only a short distance before being stopped by the faces 60 of pawl 57 which hold them in ineffective position.

10 One of the spools is constantly winding up ribbon which is being unreeled from the other spool, and when a spool is empty, the ribbon reverse mechanism becomes effective to cause the ribbon feed mechanism to engage with the empty spool 15 reversing its direction and causing it to wind up ribbon, while the driving mechanism is simultaneously disengaged from the full spool.

20 At the beginning of each ribbon reverse cycle, just as the empty spool begins its reverse motion, one of the pawls carried by bar 65 is positioned in respect to the empty spool as the pawl shown in Figure 2, the bar having been moved to this position by the previous winding up of the other spool. It should be noted that for the entire time 25 a spool is unwinding that the arm of the pawl is in the path of pins 78 which during the course of the unwinding operation engage the face 78 30 repeatedly tripping the pawl away from its stop 77, without having any other effect on the mechanism.

35 When the spool reverses on the start of the winding operation, a pin 78 engages face 73 of the pawl which is restrained from rotation in this direction by pin 77 in bar 65, and as the spool continues to rotate, bar 65 is moved longitudinally and the nose 70 at the end thereof engages the vertical face 71 of pawl 61 which is restrained from rotation in this direction by stop 64, causing latch 57 to turn on its pivot 58 against the tension of spring 59 releasing lever 44 which, under the influence of spring 51 moves toward the ribbon spool and causes the wick 50 to contact with ribbon 12 on the spool.

40 In the meantime the opposite spool is unwinding and its pins 78 are tripping harmlessly against the pawl face 72.

45 When the spool being inked has wound up to the limit, the ribbon again reverses and the second inking device is brought into contact with the ribbon in the manner just described.

50 At the start of the inking operation, toggle lever 85 was brought by the movement of lever 44 into the path of pins 78 underneath the ribbon spool where it was harmlessly tripped on its pivot 84 each time it was engaged by one of these pins.

55 With this condition, however, on the reversal of the full spool, the recess at the end of lever 85 formed by arms 86 and 87 is entered by a pin 78 with the result that with the continued rotation of the spool, due to the stops 88 of levers 85 60 which pivots both levers about 81 until lever 44 is rotated backward sufficiently for it to be engaged and retained by stop 55 on latch 52.

65 As the rotation of the spool continues, the 70 notched end of lever 85 is carried for some distance around with the spool until pin 78 becomes disengaged from the notch at the end of 85 and springs back, due to spring 82 to its normal un-operated position as shown in Figure 2.

Bar 65 is free to move in either direction according to each ribbon reversal. At each reciprocation of bar 65, a cam face 69 engages the slanting face of a pawl 61, and during the course of movement of the bar, the pawl is merely tripped away from its stop 64. At the same time, at the opposite side of the printer, the face 71 of a pawl 61 is engaged by the nose 70 at the end of bar 65 which trips latch 57 ineffectively at each ribbon reversal as long as lever 44 is retained by latch 52.

What is claimed is:

1. In a typewriting machine having a ribbon, a pair of ribbon spools therefor, and a ribbon feed mechanism, means for inking said ribbon comprising a pair of ink receptacles, each provided with a wick, an arm for supporting a receptacle pivoted adjacent to each ribbon spool, springs tending to move the arms so as to cause the wicks to engage and ink the ribbon on the respective spools, a pair of latches associated with each of said arms for retaining the receptacles and wicks out of contact with the ribbon, a first latch of each pair being manually operable to release the arm associated therewith, the second of said latches being adapted to retain said arm after its release by the first latch, and a member controlled by said ribbon feed mechanism adapted to trip the second latch of each pair alternately after each ribbon reversal.

2. In a typewriting machine having a ribbon and a ribbon feed mechanism, means for inking said ribbon comprising a pair of ink receptacles each provided with a wick, an arm for supporting a receptacle pivoted adjacent to each ribbon spool, springs tending to move the arms so as to cause the wicks to engage and ink the ribbon of the adjacent spool, a pair of latches associated with each of said arms for retaining the receptacles and wicks out of contact with the ribbon, a first latch of each pair being manually operable to release the arm associated therewith, the second latch of each pair being adapted to retain said arm after its release by the first latch in position to disable the first latch, and means controlled by the ribbon feed mechanism common to both of the second latches for releasing said arm from the second latch when the ribbon reverses.

3. In a device of the character described, a typewriting device provided with a ribbon feed mechanism including ribbon spools and ribbon reverse mechanism, an inking device for said ribbon comprising an ink saturated fabric arranged to contact said ribbon during the course of a ribbon feed operation, a support for said inking device, latch means normally effective to retain said device out of contact with said ribbon, spring means tending to cause said device to engage said ribbon, a member adapted to rotate with the ribbon feed mechanism, a lever secured to said support adapted to engage said member during the progress of an inking operation and to cooperate with said member to move said device out of contact with said ribbon against the action of the spring means into the latched position after a predetermined interval.

4. In a typewriting machine having a ribbon, a pair of ribbon spools therefor, and an automatic ribbon feed mechanism, automatic means for inking said ribbon for its entire usable length comprising a pair of ink receptacles, each being provided with a wick, a pivoted arm for supporting a receptacle adjacent to each ribbon spool, springs tending to move the respective arms so as to cause the wick to engage the ribbon on the adjacent spool, a latch associated with each arm to retain the receptacles in an ineffective position with the respective wicks out of contact with the ribbon, a member common to both latches actuated by the ribbon feed mechanism for tripping them alternately and invariably at predetermined parts of the ribbon feed cycle, and manually operated latch means for retaining each arm independently of the first mentioned latches.

5. In a typewriting device having a ribbon, automatic ribbon feed mechanism and a ribbon inking device, the combination of a pivoted bar for supporting said inking device, resilient means tending to bring said device into contact with said ribbon, a latch for holding said bar with said inking device out of contact with said ribbon, automatic means for disengaging said inking device and said ribbon comprising a rotary member, a jointed arm provided with a notched end pivoted to said bar, spring means tending to hold the edge of said arm in the path of said rotary member when the inking device is in contact with said ribbon thereby causing said arm to turn on its pivot each time it is engaged by said rotary member as the latter turns in one direction, said rotary member when turning in the opposite direction being adapted to enter the notch in said arm and with its continued rotation force the arm and bar back behind said latch and thereafter withdraw from the notch, and spring means for withdrawing said arm out of the path of said rotary member on the disengaging of the latter from said notch.

6. In a typewriting device having a ribbon, automatic ribbon feed mechanism and a ribbon inking device, the combination of a pivoted bar for supporting said inking device, resilient means tending to bring said device into contact with said ribbon, a latch for holding said bar with the inking device out of contact with said ribbon, automatic means for disengaging said inking device and said ribbon comprising a rotary member, a jointed arm provided with a notched end pivoted to said bar, spring means tending to hold the edge of said arm in the path of said rotary member when the inking device is in contact with said ribbon causing said arm to be moved on its pivot as it is engaged by the rotary member as it turns in one direction, said rotary member being adapted when turning in the opposite direction to enter said notch and force the arm and bar back sufficiently far, against the pressure of said resilient means, for the latch to engage and retain said bar.
